UNITED STATES PATENT OFFICE.

EDWARD CARLSON AND JAMES PERRIE, OF CHICAGO, ILLINOIS.

BOLSTER.

SPECIFICATION forming part of Letters Patent No. 703,993, dated July 8, 1902.

Application filed March 7, 1902. Serial No. 97,150. (No model.)

To all whom it may concern:

Be it known that we, EDWARD CARLSON and JAMES PERRIE, citizens of the United States, residing at Chicago, in the county of Cook and 5 State of Illinois, have invented certain new and useful Improvements in Bolsters, of which the following is a description.

Our invention relates to bolsters, both car and truck bolsters as to general characteristics and to truck-bolsters as to certain hereinafter-described special characteristics.

The object of such invention is to provide a bolster simple in construction, having lightness commensurate with great strength, and 15 capable of ready assembling and of convenient repairing, all of which advantages and points of utility will be apparent from the description hereinafter given.

In the accompanying drawings, Figure 1 is 20 a side elevation of a truck and car or body bolster with a portion thereof broken away to illustrate certain features of our invention; Fig. 2, a plan view of the truck-bolster; Fig. 3, a perspective of one end of the lower 25 or tension member of the truck-bolster, illustrating the manner of gibbing both web and flanges of the channel-bars; and Fig. 4, a fragmentary view of a bolster, illustrating a modified form of construction.

30 Describing first the truck-bolster, the same comprises in general terms the compression member, tension member, side plates, and the central support or post. The compression and tension members are made from channel-bars, which in the instance shown in Fig. 1 are arranged web to web, with their flanges directed away from each other, while in Fig. 4 the flanges are directed in the same direction. The compression member has a web 1 and flanges 2, and the tension member has a web 3 and flanges 4, a suitable central support or post 5 being arranged between said members. Suitable side plates 6 are riveted or otherwise secured along the sides of such 35 members. The usual column-plates 7 are also riveted to the sides thereof. The side plates 6 are desirable, but might in some instances be dispensed with. By preference the webs of the compression and tension members 40 are brought together into contact for a short distance near their ends, which are gibbed as to both their webs and flanges, whereby all

lateral movement of one member on the other is prevented and the strain properly provided for. To this end in the form shown in Fig. 55 1 each end of the web 3 of the tension member is upset, so as to have an upward flange 8 and downward flange 9. The web 1 of the compression member has a double-angled flange 10, forming a recess to receive the flange 60 8. As clearly shown in Fig. 3, the lower corners of the flanges are cut away at 2°, so as to permit the end of the bar as to its entire width, including flanges, to be turned up in the form of the flange 10 and be folded into 65 such cut-away portion and to receive the flange 8, extending full width of the tension member. The function of the depending flange 9 is to prevent lateral displacement of the spring-seat 11 for the usual springs 9, 70 which seat bears on the under side of web 3 and has a flange or shoulder 13 snugly fitting the flange 9. If desired, an end plate 14 may be secured to each end of the bolster.

Referring next to the car or body bolster, 75 the same comprises a compression member made of channel-bar having a web 15 and flanges 16 and a tension member, also made of channel-bar having a web 17 and flanges 18. The said members are also arranged web 80 to web, and the bars are gibbed as to both web and flange; but the ends here need but a single flange 19, received by the double-angled flange 20 on the other web. It is obvious that the webs 1 and 3 of the truck-bolster might be similarly flanged—that is, that the flange 9 might be dispensed with, such flange being desirable, so as to furnish an abutment or stop for the spring-seat 11.

In Fig. 4 is illustrated a modified form of 90 body-bolster, in which the flanges 21 and 22 of the upper and lower members or channel-bars, respectively, extend in the same direction—that is, downwardly instead of in opposite directions, as shown in Fig. 1—and such 95 bars have the webs 23 and 24, corresponding to the webs 17 and 15. (Shown in Fig. 1.) The ends of the channel-bars are gibbed in the same manner as those hereinbefore described.

100 By reason of the construction hereinbefore described, particularly the end gibbing as to both the web and flange, we provide a practical and serviceable bolster possessing great

strength, and, moreover, such bolster is simple in its construction and easy of assembling and repair.

We claim—

- 1. A bolster having its compression and tension members formed of two bars or plates, one of which is provided with end flanges and the other one of which is provided at its ends with double-angled flanges engaging said first-named flanges; substantially as described.
- 2. A bolster having its compression and tension members formed of channel-bars gibbed at their meeting ends as to both their webs and flanges; substantially as described.
- 3. A bolster having its compression and tension members formed of channel-bars arranged web to web with their flanges outwardly directed, said members being gibbed as to their ends.
- 4. A bolster having its compression and tension members arranged web to web, the ends of said members being gibbed; substantially as described.
- 5. A bolster having its compression and tension members arranged web to web with their meeting ends gibbed and plates secured to the sides of said members; substantially as described.
- 6. A bolster having its compression and tension members arranged web to web, the web of one member having a flange and the web of the other member having a double-angled flange receiving the first-mentioned flange; substantially as described.
- 7. A truck-bolster having compression and tension members gibbed together at their ends, spring-seats, and means on the ends of each tension member to hold said seats in place; substantially as described.
- 8. A truck-bolster having its compression

and tension members gibbed together at their ends, spring-seats, and a flange on the ends of each tension member to hold said seats in place; substantially as described.

9. A truck-bolster having a compression 45 and a tension member formed of channel-bars, and spring-seats, the end of the web of the tension member being upset to form a flange both above and below the web, the end of the other web bearing against the upper 50 flange whereby the said members are gibbed together at their ends and the spring-seats bearing against the lower flange and held in place thereby; substantially as described.

10. A truck-bolster having a compression 55 and a tension member, and spring-seats, the end of the web of the tension member being upset to form a flange both above and below the web, the end of the web having a double-angled flange receiving the upper flange of 60 the tension member and the spring-seats bearing against the lower flange; substantially as described.

11. A truck-bolster comprising a compression member having a web 1 and flanges 2, a 65 tension member having a web 3 and flanges 4, the members being arranged web to web, a central support, the web 3 being upset to form upper and lower flanges 8 and 9 and the web 1 having a double-angled flange 10 to fit 70 the flange 8, and a spring-seat 11 bearing against the under side of the web 3 and having a flange 13 fitting against the flange 9; substantially as described.
